UNITED STATES PATENT OFFICE

JOSEPH KINTZ, OF WEST MERIDEN, CONNECTICUT, ASSIGNOR TO HIMSELF
AND P. J. CLARK, OF SAME PLACE.

DESIGN FOR BRACKET-CUP FOR CHANDELIER.

Specification forming part of Design No. **8,053**, dated February 9, 1875; application filed January 4, 1875.
[Term of Patent 14 years.]

To all whom it may concern:

Be it known that I, JOSEPH KINTZ, of West Meriden, New Haven county, Connecticut, have invented a new and Improved Design for the Cup or Basket of a Bracket or Chandelier, of which the following is a specification:

The nature of my design is fully represented in the accompanying drawing, to which reference is made—

Figure 1 being a sectional view, and Fig. 2 a plan of the cup or basket.

D represents the ordinary basket, which I ornament with a crown-piece consisting of the annular perpendicular rim A and downwardly-

oblique flange A', arranged to rest at their junction upon the turned edge of basket.

To the eye there is thus presented a more finished appearance, a more perfect outline, and a more ornamental aspect.

What I claim is—

A design for ornamenting the top of a bracket or chandelier, consisting of a crown-piece having annular rim A and oblique projection A' seated at their junction upon the turned edge of basket, as shown and described.

JOSEPH KINTZ.
